BOOKMARK

William G. Albrecht, Jr., Baltimore, Md.

Application January 6, 1948, Serial No. 735

4 Claims. (Cl. 281—42)

1

This invention relates to a bookmarker, and more particularly is designed and adapted for use as a marking device in association with a looseleaf binder, ledger book, appointment pad, or similar memoranda or recording pads or books.

The principal object of this invention is to adequately facilitate the marking of a book or pad without injury to the book or the pages therein, and at the same time, to securely retain in a position adjacent the book or pad, a writing implement or instrument.

Another object of this invention is to provide a combination bookmarker and writing implement holder, which is integrally formed with a page of a book, or more particularly with a looseleaf page, insertable within a looseleaf binder or the like.

Another object of this invention is to provide a simple and efficient bookmarker, in combination with a writing implement holder, which is conveniently detachably or permanently secured within a book or looseleaf binder and which is durable and efficient in operation.

These and ancillary objects are attained by this invention, a preferred embodiment of which is set forth in the following description, by way of example only, and illustrated in the accompanying drawings, wherein:

Figure 1 is a plan view of a looseleaf page, showing a bookmarker and writing implement holder integrally formed therewith, the marker and writing implement container being constructed in accordance with the principles of this invention;

Figure 2 is a plan view in perspective of the combined looseleaf page, bookmarker and writing implement holder;

Figure 3 is a transverse sectional view of Figure 2, showing in more detail the laminated page and holder;

Figure 4 is a plan view of a modification of this invention;

Figure 5 is a perspective view of a bookmarker and pencil holder, constructed according to this invention, and shown in attachment with a looseleaf binder; and

Figure 6 is another modification of this invention in plan view.

Various types of memorandum pads, ledger books, purchase and consignment books and other official recording books are constructed and arranged in the form of a looseleaf binder, of suitable sturdy material, comprising a pair of opposed outer covers, joined by a plurality of vertically spaced rings or the like. These books and

2

similar other pads are employed for particular recording purposes and, as such, usually contain a number of blank lines or spaces, which are to be filled in by the user with the necessary data.

Thus, a user, when utilizing the book or pad, is at all times turning from one page to another to record the information or to calculate or evaluate the already recorded data.

Thus, it is the primary purpose of this invention to provide a bookmarker for such a pad or book and to provide in association with the bookmarker means for retaining a writing implement or instrument in close proximity to the book or pad, so that the user will at all times have a writing instrument handy for adding data to the pad or book.

A meritorious feature of this invention resides in the provision of a pliable and flexible bookmarker, which is formed integrally with a page of the looseleaf binder and which projects outwardly therefrom. An intermediate connecting portion is provided to connect the offset bookmarking portion with the page of the book and is suitably scored so as to be entirely flexible to enable the bookmarker to be positioned in any of the pages of the book. The intermediate portion also serves a dual purpose, in that it provides means whereby a pencil may be retained adjacent the book for ready utilization.

Referring now more particularly to the drawings, wherein similar characters of reference designate corresponding parts throughout, and in particular to Figures 1 to 3, inclusive, wherein a preferred embodiment of this invention is set forth, by way of illustration only, 10 designates the unitary looseleaf page, bookmarker and writing implement retainer. The unitary section may be formed of any suitable pliable material, which is flexible and yet sturdy, such as oil-treated paper, cardboard or the like. The unitary device

10 comprises a pair of juxtaposed blanks 12 and 14 which are of similar shape and design and are suitably joined together by conventional means such as adhesive, paper glue, or the like.

The blank 12 comprises an elongated rectangular body or page section 16, of any suitable width and length, dependent upon the size of the looseleaf holder and having longitudinally extending opposed sides 18 and 20. Medially projecting from the side edges 18 of the body section 16 is an intermediate connecting member 20, having suitable vertical scoring imposed thereon, so as to render the intermediate connecting member or section 20 flexible. The intermediate portion 20 has integrally formed on its opposite end an

extending or projecting offset or marking section 22. The marking section 22 is elongated and of a width similar to that of the body or page section 16. At the juncture point of the intermediate connecting section 20 and the marking section 22 there are disposed opposing arcuate shoulders 24 and 26.

Blank 14, having a similar body or page section 34, an intermediate connecting section 28 and an offset marking section 30, is suitably adhered to the blank 12 so as to form the laminated unitary structure 18. The opposed intermediate connecting sections 20 and 32 are unattached and form a sleeve 32, whereby a writing instrument or implement may be frictionally held therein. Thus, with reference to Figure 1 of the drawings, there is shown a pencil 36 frictionally retained or held within the sleeve 32, with the bookmarking offset section, 38, formed of the laminated offset sections 22 and 30, which are securely adhered together, folded over on the body or page section, 40, formed from the body sections 12 and 14, which are suitably secured in juxtaposition.

Suitable means are provided to detachably or permanently secure the body or page section 40 within a looseleaf binder and includes a plurality of vertically spaced longitudinally extending openings or apertures 42, formed in the longitudinal side of the body sections 12 and 14, opposite the intermediate section, and adjacent the free side thereof. The aligned apertures 42 serve as a retaining means for the marker and writing implement holder and are secured to a looseleaf holder by inserting the rings or similar binding means within the openings or apertures 42.

Thus, it can be seen that the laminated page or body section 40 may be secured within a looseleaf holder, either at the front, the middle or the rear section thereof, by means of the spaced vertical openings 42, and thus, at all times, the bookmarker 36 and the pencil-retaining sleeve 32 will be disposed in an operative and convenient position.

Referring now to the modification illustrated in Figure 4 of the drawings, there is shown a unitary laminated pliable and flexible blank 50, having an oblong body or page section 52, which has a plurality of vertically spaced apertures or openings 54 disposed adjacent to the free side, 56, thereof. The opposing side 58 of the body or page section 52 has its corner edges rounded and is integrally connected with a sleeve 60. The sleeve or intermediate portion 60 serves as a connecting link or section between the body or page piece 52 and an offset angular marking or positioning section or piece 62. The intermediate or connecting sleeve 60 has a pair of opposed vertically spaced arcuate apertures or openings 62 and 64 formed adjacent the open ends thereof. The arcuate openings 62 and 64 in the opposed sides of the sleeve 60 define or form opposed end straps 66 and 68 and intermediate opposed connecting flaps 70. Thus, with reference in particular to Figure 4, it can be seen that a pencil or similar writing instrument 72 is positioned within the sleeve 60 and is securely frictionally retained therein by means of the opposed straps 66 and 68 and the opposed connecting flaps 70, which serve to strengthen the connection between the body section 52 and the offset marking section 62. By forming the sleeve with the opposed strap sections 66 and 68 and the opposed intermediate connecting flaps 70, the connection is rigidified and the retaining strength of the sleeve

is increased, as the opposed straps 66 and 68 serve to individually retain the pencil at each end of the sleeve and the opposed connecting flaps 70 serves to retain the pencil or similar writing instrument, 72, in the main portion of the sleeve. Also, the arcuate openings 62 and 64 serve to provide viewing spaces, so that commercial indicia or other advertising matter, subscribed on the writing instrument, may be perceivable.

As shown in Figure 5 of the drawings, the unitary laminated bookmarker and writing implement retainer 50 is secured within a looseleaf binder or holder 76 by means of the connecting rings 78, which are inserted through the openings or apertures 54 formed in the free end 56 of the body or page section 52.

Referring now to Figure 6 of the drawings, wherein another modification of this invention is set forth, there is shown a marker similar to that of the marker 50 disclosed in Figure 4 of the drawings and having a body or page section 80, having rectangular or angular apertures or openings 84 formed on the free end thereof. An offset oblong marker or pointing section 86 is integrally connected with the body or page section 82 by means of an intermediate connecting portion or sleeve 88. The intermediate connecting sleeve 88 is formed of opposed strips of pliable flexible material, medially and integrally secured to the marking section 86 and the body section 82, and having vertical scoring 90 disposed thereon, rendering the intermediate connecting portion or sleeve 88 flexible and pliable so that the marker section 86 may be moved in angular or arcuate movement to be secured in marking position, in any desired position or placed on any page within the book.

Thus, it is apparent that there has been provided a simple, efficient and durable bookmarking device, which is integrally formed with a filler page or page insert for a looseleaf binder or the like. The provision of a sturdy and flexible bookmarker also incorporates the provision of a writing implement or instrument retaining means in association therewith. Accordingly, the employment and utilization of the permanently attached bookmarker and writing implement retainer, formed integrally with a page or filler page of a book binder, renders more convenient and speedy the task of a user of a ledger book, such as a bookkeeping or accounting book.

Since many other purposes and modifications of this invention will become apparent to those skilled in the art, upon a perusal of the foregoing description, in view of the accompanying drawings, it is to be understood that this invention imparts nothing by way of limitation, but that suitable changes in size, style or arrangement of parts may be effected without a departure from the spirit of the invention and within the scope of the appended claims.

Having thus described the invention, what is claimed as new is:

1. A bookmarker comprising a unitary laminated blank, forming a body section, a marking section laterally projecting from one of the longitudinal side edges of the body section and adapted to swing inwardly thereof, an intermediate sleeve hingedly connecting said body section and marking section, vertical scoring on the opposed sides of the sleeve, vertically spaced openings disposed on the free side of the body section for securing the body section within a book binding, and means for frictionally holding

a writing instrument within the intermediate sleeve.

2. A bookmarker comprising a unitary laminated blank forming a rectangular body section, a marking section projecting laterally from the medial portion of one of the longitudinal side edges of the body section, an intermediate sleeve portion hingedly connecting the body section and marking section, whereby a writing instrument may be held therein, and means for securing the body section to a book.

3. A bookmarker comprising a unitary laminated blank forming a body section, an elongated offset marking section projecting laterally from one of the longitudinal side edges of the body section, an intermediate sleeve portion hingedly connecting the body section and marking section, and adapted to frictionally retain and embrace a writing instrument, means for securing the body section to a book, said sleeve being formed with opposed arcuate openings vertically spaced therein, and transverse binding strips disposed adjacent said openings.

4. In combination with a loose-leaf notebook having front and rear covers and a filler between the covers, a book marker mounted to swing as

a leaf between the covers and including a body section having means disposed adjacent one of the longitudinal sides thereof for securing the same between the covers, a reduced marking strip swingably carried by the opposing side edge of the body section, a flexible intermediate connecting sleeve disposed between the body section and strip, said sleeve being formed at its upper and lower ends with opposed openings, binding strips being disposed between the body section and the marking strip above and below the openings in the sleeve.
